(57) **CLAIM**

The ornamental design for an automated system controller, as shown and described.

DESCRIPTION

FIG. 1 is a perspective view of an automated system controller for illustrating our new design;

FIG. 2 is a bottom perspective view thereof;

FIG. 3 is a top view thereof;

FIG. 4 is a bottom view thereof;

FIG. 5 is a side view thereof;

FIG. 6 is a second side view thereof;

FIG. 7 is an end view thereof;

FIG. 8 is a perspective view of an alternative embodiment of the automated system controller further illustrating our design;

FIG. 9 is a bottom perspective view of the embodiment shown in FIG. 8;

FIG. 10 is a top view of the embodiment shown in FIG. 8; and,

FIG. 11 is a side view of the embodiment shown in FIG. 8.

The broken lines showing is for the purpose of illustrating unclaimed portions of the automated system controller and forms no part of the claimed design.
